The ornamental design for handle unit for radiation detecting probe, as shown.

DESCRIPTION

FIG. 1 is a side elevational view of the handle unit for the radiation detecting probe showing my new design, the opposite side being identical thereto;

FIG. 2 is a top plan view thereof;

FIG. 3 is a bottom view thereof;

FIG. 4 is a front view thereof; and,

FIG. 5 is a rear view thereof.

The broken line showing is for illustrative purposes only and forms no part of the claimed design.
